UNITED STATES PATENT OFFICE.

WILLIAM E. BROOKS AND BOYD S. EPPES, OF BATTLE CREEK, MICHIGAN.

CONTAINER.

1,411,475.

Specification of Letters Patent.

Patented Apr. 4, 1922.

Application filed April 25, 1919. Serial No. 292,756.

To all whom it may concern:

Be it known that we, WILLIAM E. BROOKS and BOYD S. EPPES, citizens of the United States, residing at 27 W. Fountain St.,

5 Battle Creek, county of Calhoun, State of Michigan, have invented certain new and useful Improvements in Containers, of which the following is a specification.

This invention relates to improvements 10 in containers.

The main objects of this invention are:

First, to provide an improved display box or container which may be employed for shipping and storing goods and also as

15 a display box or container providing a transparent panel through which the goods are visible.

Second, to provide an improved display box or container having these advantages 20 in which the body of the box may be formed of paper board or the like, the window being transferred from one box or container to another, so that the goods are kept in and sold from original packages, the window being inserted from the outside of the 25 box or container without handling or disturbing its contents, and the packages being neat and attractive.

Further objects, and objects relating to 30 structural details, will definitely appear from the detailed description to follow.

We accomplish the objects of our invention by the devices and means described in the following specification. The invention 35 is clearly defined and pointed out in the claims.

A structure which is a preferred embodiment of our invention is clearly illustrated in the accompanying drawing forming a 40 part of this specification, in which:

Fig. I is a front view of the box or container before the part removable to provide a window opening is removed.

Fig. II is a front view of the same box 45 or container with the window or transparent panel in place.

Fig. III is a detail horizontal section on a line corresponding to line 3—3 of Fig. II.

Fig. IV is a detail vertical section illustrating the manner of introducing and removing the window.

Fig. V is a detail vertical section on a line corresponding to line 5—5 of Fig. II.

Fig. VI is a detail vertical section on a 55 line corresponding to line 6—6 of Fig. II.

In the drawing, similar reference char-

acters refer to similar parts throughout the several views, and the sectional views are taken looking in the direction of the little arrows at the ends of the section lines.

60

Referring to the drawing, the box or container 1 is shown mainly in conventional form. Its front wall 2 has a portion 3 partially severed along its edges 4 to facilitate its removal to provide a window opening 7, 65 the line of severing being indicated by dotted lines. The removable part 3 has a recess 5 at its upper edge providing when the part 3 is removed a tongue 6 on the upper edge of the opening 7.

70

The transparent pane or panel 8 may be of glass, celluloid, or other material. We provide a supporting frame 9 therefor, which, in the structure illustrated, is formed of sheet metal. Parts of the inner edges 75 of the frame are turned rearwardly at 10, then outwardly at 11, then rearwardly at 12, then inwardly at 13, providing outwardly facing grooves 14 adapted to receive the edges of the opening so that the frame is removably engageable therewith and inwardly facing grooves 15 engaging the edges of the panel 8.

The frame engaging members are disposed so that the tongue 6 projects between 85 the panel and the frame as shown in Figs. II and IV. The wall engaging grooves are of such depth as to permit a vertical and horizontal telescoping movement of the frame with the edges of the opening permitting its being passed through the opening—see Fig. IV, and when in position shifted to engage all the edges, thus providing a convenient means of introducing and retaining the frame.

95

Our improvements enable the sale of goods direct from the shipping containers or cartons and at the same time effectively displays the goods in the original packages.

As packages handled in the sale of goods soon become more or less soiled and shelf worn with use, by the aid of our improvements it is practical to provide an attractive display package from the original containers in which they are shipped which

100 may be thrown away when the contents of the container are exhausted. The more expensive portions and the portions which

105 would be likely to be injured in shipping may be removed and used on the new pack-

age or container.

110 We have not attempted to illustrate or

describe various modifications or adaptations which we contemplate, as we believe the disclosure made will enable those skilled in the art to which our invention relates to 5 embody or adapt the same as may be desired.

Having thus described our invention, what we claim as new and desire to secure by Letters Patent, is:

- 10 1. The combination of a container having a panel opening in a wall thereof with a centrally disposed projecting tongue on its upper edge, a transparent panel, and a supporting frame therefor comprising a body portion lying flat against the container wall around said opening, and having portions of its inner edges turned rearwardly, then outwardly, then rearwardly, then inwardly providing continuous inwardly facing inner grooves engaging the edges of the panel, and continuous outwardly facing outer grooves telescopically engaging all the edges of said opening, the frame body portion constituting the front wall of said outer grooves, 15 there being an opening in the inner edge of the upper wall engaging groove through which said tongue projects in overlapping relation to said panel.
- 20 2. The combination of a container having a panel opening in a wall thereof, a transparent panel and a supporting frame therefor comprising a body portion lying flat against the container wall around said opening, and having portions of its inner edges 25
- 30

turned rearwardly, then outwardly, then rearwardly, then inwardly providing continuous inwardly facing inner grooves engaging the edges of the panel, and continuous outwardly facing outer grooves telescopically engaging all the edges of said opening, the frame body portion constituting the front wall of said outer grooves. 35

3. The combination of a container comprising a wall having a panel opening therein, there being a substantial portion of the 45 wall on all sides of said opening, with a projecting tongue at one side thereof, a transparent panel, and a supporting frame for said panel provided with outwardly facing grooves removably and telescopically engaging all of the edges of the panel opening whereby the frame may be shifted laterally to facilitate the introduction and removal of the panel through the opening and the engagement and disengagement of the frame 50 with the edges of the opening and providing a closed joint between the frame and the edges of the opening when the panel is in position.

In witness whereof, we have hereunto set 60 our hands and seals in the presence of two witnesses.
